MINIATURE CANNON

Filed Sept. 11, 1933

BY

INVENTOR
George E. Wade,

S. G. Fischer,
ATTORNEY.

UNITED STATES PATENT OFFICE

2,046,663

MINIATURE CANNON

George E. Wade, Independence, Mo.

Application September 11, 1933, Serial No. 688,865

1 Claim. (Cl. 42—55)

My invention relates to miniature cannons and one object is to provide a device of this character which will make a loud report when fired, and may be safely used by children.

5 One feature of the invention resides in obstructions for preventing the introduction of large missiles such as wadding, marbles and the like, into the barrel of the cannon and which will break up into relatively small and harmless particles smaller missiles so introduced.

10 Another feature resides in a simple and inexpensive firing mechanism for exploding the charge of ammunition introduced into the firing chamber of the barrel.

15 A further feature resides in safety seats for the breech end of the barrel, said seats being adapted to receive the shock caused by the recoil of the cannon when fired and thereby prevent injury to the trunnions carrying the barrel and 20 which are mounted in a carriage containing said seats.

25 Other features will hereinafter appear and in order that the invention may be fully understood, reference will now be had to the accompanying drawing, in which:

Fig. 1 is a side elevation of the cannon.

Fig. 2 is a plan view of the cannon with a portion broken away to show one of the seats for the breech end of the cannon barrel.

30 Fig. 3 is a vertical longitudinal section of the barrel with the firing mechanism associated therewith in elevation.

Fig. 4 is a cross section on line 4—4 of Fig. 1, showing obstructions in the forward portion of 35 the bore of the barrel.

Fig. 5 shows the different elements constituting the firing mechanism of the cannon ready for assembly.

40 Referring in detail to the different parts, 2 designates the barrel of the cannon which has a longitudinal bore 4 in the forward end of which are obstructions in the form of oppositely-disposed parallel ribs 6 for the purpose of preventing large missiles such as marbles, wadding and the like from being introduced into the bore 4. In the event smaller missiles are introduced into the bore 4 they will be broken up into minute and relatively harmless particles by the ribs 6 which have narrow longitudinal edges 8 to render them more effective for that purpose.

45 The barrel 2 is provided at its breech end with a simple firing mechanism comprising a firing pin 10 provided at its upper end with a head 12, a bushing 14 threaded into the barrel 2 and in which the firing pin 12 is reciprocably mounted, a nut 16 threaded upon the lower end of the firing pin 10, and a coil spring 18 interposed between the head 12 and the enlarged upper end 50 of the bushing for the purpose of normally

holding the firing pin in the raised position disclosed by Figs. 1 and 3. The upward movement of the firing pin 12 is limited by the nut 16 contacting the lower end of the bushing 14. The construction of the firing mechanism permits 5 complete assembly thereof before being installed in the barrel 2.

The barrel 2 is provided about midway between its muzzle and breech ends with a pair of oppositely-disposed trunnions 22 pivotally mounted in bearings 24 forming part of a suitable carriage comprising a body 26 carrying the bearings 24, an axle 28, and a pair of wheels 30 mounted upon said axle.

The body 26, which is bifurcated at its upper 15 forward portion, has seats 32 in the form of recesses at the opposite sides of said bifurcated portion into which the breech end of the barrel snugly fits so that when the cannon is fired the resulting jar from the explosion and a hammer 20 striking the head 12 of the firing pin 10 will be imposed upon said seats 32 instead of the trunnions 22 and thereby prevent injury to the latter.

In practice ammunition such, for instance, as a proper mixture of sulphur and potash, which 25 explodes when subjected to a sudden impact, is introduced into the firing chamber 34 through the muzzle end of the barrel 2. The head 12 of the firing pin 10 is then struck sharply with a hammer or other suitable object to force said 30 firing pin inwardly so that its inner end and the nut 16 will impinge against and detonate the ammunition.

From the foregoing description it is apparent 35 that I have provided a miniature cannon embodying the advantages above pointed out, and while I have shown and described one embodiment of the invention I reserve all rights to such changes and modifications thereof as properly fall within the spirit and scope of the invention as claimed. 40

Having thus described my invention, what I claim and desire to secure by Letters Patent, is:

In a cannon of the character described, a barrel suitably mounted, a firing mechanism arranged transversely in the rear portion of the barrel and comprising a bushing threaded into the upper wall of said barrel, a firing pin reciprocably mounted in said bushing and projecting above the barrel, a head on said firing pin adapted to be struck to force the firing pin downwardly to detonate an explosive charge in the firing chamber of the barrel, an expansible spring interposed between the bushing and said head to raise the firing pin after it has been forced downwardly, and means on the firing pin for contacting the lower end of the bushing to limit the upward movement of said firing pin. 55

GEORGE E. WADE.
